United States Patent Office

Des. 192,893
Patented May 22, 1962

192,893

CAN CARRIER

Rex L. Brunsing, 260 California St., San Francisco, Calif.

Filed Nov. 21, 1960, Ser. No. 62,908

Term of patent 14 years

(Cl. D58—17)

FIG. 1

FIG. 2

FIG. 3

FIG. 4

FIG. 5

FIG. 6

FIG. 1 is a top plan view of a can carrier, showing my new design;

FIG. 2 is a bottom plan view thereof;

FIG. 3 is a side elevational view thereof;

FIG. 4 is an end elevational view thereof;

FIG. 5 is a cross sectional view taken along line 5-5 of FIG. 1;

FIG. 6 is a cross sectional view taken along line 6-6 of FIG. 1;

I claim:

The ornamental design for a can carrier, as shown.
